DARNING LIGHT

Alonzo J. Bloodgood, Middlebury, Conn., assignor
of one-third to John S. Michelson, Bridge-
port, Conn., and one-third to J. Harvey
Chandler, Middlebury, Conn.

Application August 6, 1940, Serial No. 351,594

2 Claims. (Cl. 240—2)

This invention relates to a device for supporting an article while it is being darned to facilitate the darning operation, and has for an object to provide an article of this type of improved shape to facilitate the darning operation and which also will be illuminated to still further facilitate this operation.

It is also an object to provide an improved construction and arrangement of darning head which in addition to being illuminated, will have improved means for holding the illuminated head, and which means can be utilized as a container for darning yarn, needles and other articles.

It is a further object to provide an improved illuminated darning holder which may be constructed almost entirely of molded non-metallic plastics so that it may be made of different colors and finishes, may be of light weight, practically unbreakable in normal handling, and may be made and sold at low cost.

With the foregoing and other objects in view I have devised the construction illustrated in the accompanying drawing forming a part of this specification. It is, however, to be understood that I am not limited to the specific details shown, but may employ various changes and modifications within the scope of the invention.

In this drawing:

Fig. 1 is a partial side elevation and partial longitudinal section through my improved darning light;

Fig. 2 is a top plan or end view thereof;

Fig. 3 is a transverse section substantially on line 3—3 of Fig. 1;

Fig. 4 is a view looking toward the lower end of the handle with the cap removed;

Fig. 5 is a transverse section substantially on line 5—5 of Fig. 1;

Fig. 6 is a detail section substantially on line 6—6 of Fig. 4 on an enlarged scale; and

Fig. 7 is a similar section substantially on line 7—7 of Fig. 4.

This darning light comprises a head 10, preferably made in two parts, a body 11, and a cap 12 secured together by a tight joint 13. This head may be made of various materials but is preferably made of some one of the moldable plastics now available on the market, such for example as the synthetic resins and the like, and is preferably white or of a light color, and the walls sufficiently thin to be translucent, particularly the walls of the cap 12. This cap is shaped to form a support for an article 14 to be darned such for example as socks or stockings, and the head is preferably substantially circular as shown in

Fig. 2 with convexly curved side walls 15 and a concave top or end wall 16, with the ridge 17 formed at the junction of the convex wall 15 and the concave wall 16 provided with a series of notches 18 for the passage of the darning needle 19 to thus greatly facilitate the darning operation. These notches are preferably provided throughout the periphery of this ridge as shown in Fig. 1, although only a part of them are shown in Fig. 2 to simplify the drawing, the dot and dash lines 18a being to indicate these notches are provided around the entire periphery.

Also, to facilitate the darning operation this translucent head is illuminated from the interior by an electric lamp 20. This may be mounted in any suitable way, but a convenient way of mounting is to provide the neck portion 21 of the body 11 with a longitudinal passage 22 in which may be inserted the metal screw shell or lamp socket 23 having a sufficiently tight friction fit in the passage to retain it therein, and into which the screw shell base 24 of the lamp may be threaded. The central lamp contact 25 may engage contact 26 carried by an insulating disc 27 mounted in the lower end of the socket 23, as for example by being supported on the lower end wall 28 having a central opening for the lead wire 29, and the other lead wire 30 may be connected to the shell 23.

The neck 21 is reduced at its lower end for telescoping engagement with the upper end of the handle 31 as shown at 32. This handle 31 may be of any suitable material but is also preferably of a molded plastic material of any desired color. It is made hollow to carry supplies of darning yarn and also needles. Thus on its inner surface are formed spaced longitudinally extending ribs 33 forming between them grooves or compartments 34 and 35. Inserted in this handle is a tube or sleeve 36 of any suitable material such for example as cardboard fitting the free edges of the ribs 33 and the upper end 37 of the handle. This sleeve forms with the grooves 34 chambers, closed at their upper ends but open at their lower ends, to hold needles 38. The lower ends of these chambers may be closed by a disc 39 of metal or other suitable material having a notch 40 which may be brought into alignment with any of the chambers 34 to permit insertion or removal of the needles. This disc can rest against the end of the sleeve 36 as shown in Figs. 6 and 7 also against the ends of the ribs 33 and to be of a diameter to be a sliding fit in the recessed end 41 of the handle shell. It may be held in position by a spring wire ring 42 seating in a groove in the inner wall 41 to retain this disc

in position, the ring 42 being a split ring to permit its contraction for insertion and removal, and to permit it to spring into position in the groove. A lug 43 may be provided on this disc or flat ring 39 to be gripped by the operator for turning this member 39 to any desired position to carry the notch 40 to alignment with any of the chambers 34. When this notch is in alignment with the chamber 35 all of the needle chambers 34 will be closed. The chamber 35 may be used to hold the lead wires 44 connected to the lamp socket contacts 23 and 26 and with a suitable plugin cap 45 for plugging into any suitable outlet receptacle. The leads 44 may be passed through an opening in a side wall of the handle shell 31. The interior of the tube 36 provides space to hold spools 46 of darning yarn which may be inserted through the opening in the ring 39.

The lower end of the handle 31 may be closed by a cap 47 of any suitable material telescoped in the lower end of the shell as indicated at 48. It is preferred to make this cap also of a molded plastic material and it may be of the same or a different color as the handle 31. It is also preferably shaped to form a socket or chamber to hold a thimble 49. To prevent overheating of the head the wall of the body 11 is preferably provided with vent openings 50 to permit the circulation of air.

The device makes a very effective support for the article to be repaired during the darning operation, and the illuminated head together with

its new shape and needle notches 18 greatly facilitates this darning operation. As it may be made almost entirely of a light molded plastic material it is of light weight and may be made in attractive colors. It also can be made at relatively low cost, and the handle construction permits its utilization as a storage space for needles, darning yarn, a thimble and the like, which are easily accessible at any time.

10 Having thus set forth the nature of my invention, what I claim is:

1. A device of the character described comprising a hollow head of the translucent material forming a support for an article being darned, said head being substantially circular with convexly curved side walls and a concave end wall forming a depression, the periphery of the depression being of less diameter than the largest diameter of the head so that there is a convexly curved article supporting surface outwardly of said periphery, said periphery being provided with a series of open notches extending transversely thereof to the depression for passage of a needle, and an electric lamp for illuminating the interior of the head.

2. A device of the character of that defined in claim 1 in which the head is divided transversely on the convexly curved surface and in which the outer section is removable to give access to the lamp.

ALONZO J. BLOODGOOD.
